Paul A. Blair

Attorney

UNITED STATES PATENT OFFICE.

JOHN WALLACE NEFF, OF EASTON, PENNSYLVANIA.

SAFETY PAPER.

Application filed October 24, 1923. Serial No. 670,539.

To all whom it may concern:

Be it known that I, JOHN WALLACE NEFF, citizen of the United States, residing at Easton, in the county of Northampton and State of Pennsylvania, have invented certain new and useful Improvements in Safety Paper, of which the following is a specification.

This invention relates to improvements in safety papers, and methods of making the same, and more particularly to safety paper for documentary papers and negotiable instruments, although I do not wish to be limited to that specific use.

In paper for this general use, it is necessary to protect users thereof from fraudulent alterations of the matter printed or written thereon, by providing a paper which will show a change of appearance or color upon the application of a chemical designed for alteration purposes. Certain types of safety papers are now on the market on which are printed visibly in ink a word, such as "Void" or "Canceled", and which latter are rendered invisible or nearly so by the application of a fugitive tint design applied thereover, which is chemically or mechanically removed upon application of an eradicating substance. Other paper has impregnated therein, generally in the pulp stage, a chemical substance having the characteristics of a fugitive tint, either colored or otherwise, which changes appearance upon the application of altering or removing substances or solutions, but the chemicals used in this paper can be bleached off again by one aware of their presence. In all of these types of paper, however, the obvious disadvantage of many operations in manufacture is present, and, likewise, the alteration preventative characteristics are more or less discernible and removable to one desiring to alter the paper, such as a forger.

A main object of my invention, then, is to provide a safety paper which is extremely sensitive to eradicating solutions, so that the use of such will result in easy and speedy discernment.

A further object of my invention is to provide in a safety paper a means of detection of fraudulent alterations, which means, being once discernible, cannot be removed or obscured without destroying the paper itself.

A further object is to provide a safety paper having properties therein which will show an attempt at alteration, but which properties are not discernible before alteration.

A further object is to provide a safety paper which will not deteriorate with use nor age, while, at the same time, retaining the sensitiveness to altering substances.

A further object of my invention is to provide a safety paper which affords a high degree of protection, but involves a minimum of manufacturing cost.

A further object is to provide in a safety paper a means of detection of fraudulent alterations, which means may be applied to the paper at any stage of its manufacture, as, for instance, before or after sizing, with equal efficiency and utility resulting therefrom.

Other objects will be in part obvious from the annexed drawing and in part indicated from the following analysis of the invention, in which reference is made to the accompanying drawing illustrating one embodiment of my idea.

In the drawing—
Figure 1 shows a portion of paper having invisible and warning indicia therein shown in dotted lines; and;

Figure 2 designates a portion of paper after an eradication solution or substance has been applied for alteration purposes.

My invention accordingly consists in printing with a colorless and ineradicable chemical solution a word such as "Canceled", or "Void" on paper to be protected, in such a way that these words or other warning indicia are normally not visible. Upon the application of a bleaching chemical, or so-called ink eradicators, a chemical reaction is set up which causes the invisibly printed word to change color and to be readily discernible.

The most satisfactory solution for the invisible printing agent which I contemplate using is a colorless aniline solution, such as a solution of aniline hydrochloride ($C_6H_5NH_2HCl \cdot H_2O$) or, as more commonly designated, of aniline-chloride or aniline salt. In order to make this solution more stable and lasting in printing, I propose to make the same slightly acidic by adding a small quantity of a suitable acid, such as sulphurous or muriatic. The proportion of the materials

comprising the aniline solution is unimportant so long as the same is clearly, though invisibly, impressed upon the paper.

In the drawings, 10 represents a paper suitable for use in documentary or negotiable instruments, having impressed thereon by printing rollers or the like invisible words "Canceled", as at 11, in colorless form as by the aniline-chloride solution hereinbefore described. Upon the application of, or the washing in, a bleaching agent, such as ink eradicator for altering purposes the chemical reaction set up produces with the aniline-chloride solution what is known as "aniline-black", and the words stand out in a black or dark brown color, clearly discernible, as at 12. The "aniline black", being once established and brought out in the paper, can be removed or destroyed only by boiling in sulphuric acid, which would, of course, destroy the paper.

The addition of the sulphurous or muriatic acid is not essential to my invention, but adds to the body and stability of the warning indicia. So, also, I do not wish to limit myself to the use of aniline-chloride, as any colorless aniline solution, or any other chemical solution which, upon the application of eradicators, would produce an ineradicable impression, would function as efficiently.

It is seen from the above that my improved safety paper and the method of producing the same presents many advantages over the types of safety paper now in use. The invention can be applied to any kind of paper with equal facility, as no special paper is needed, and, when applied, cannot be discerned. In manufacture and preparation, it is evident that the invisible lettering can be applied by the ordinary printing roll, using the aniline solution in place of ink thereon, and no special type of machinery is, therefore, necessary. Further, the application of the solution is completed in a single operation, whereby the plurality of operations necessary in other types of safety papers is obviated. The aniline solution can be applied at any time during the preparation of the paper, and could even be applied to a sized paper without injury or discernment of the same.

Without further analysis, the foregoing will so fully reveal the gist of this invention that others can, by applying current knowledge, readily adapt it for various applications without omitting certain features that, from the standpoint of the prior art, fairly constitute essential characteristics of

the generic or specific aspects of this invention, and, therefore, such adaptations should, and are intended to be, comprehended within the meaning and range of equivalency of the following claims.

I claim:

1. A safety paper having invisible warning indicia printed thereon with a colorless chemical salt, said indicia being rendered visible when the paper is treated with bleaching agents. 65

2. A safety paper having invisible warning indicia printed thereon with a colorless aniline salt, said warning indicia adapted to be rendered visible when the paper is treated with bleaching agents. 70

3. A safety paper having invisible warning indicia printed thereon with a colorless aniline-chloride compound, said warning indicia being rendered clearly visible when the paper is treated with bleaching agents. 75

4. A safety paper having invisible warning indicia printed thereon with a colorless aniline-chloride compound, said aniline-chloride compound being slightly acidic. 80

5. A safety paper having printed thereon invisible warning indicia with a colorless aniline-chloride compound and a small quantity of sulphurous acid, said warning indicia being clearly discernible upon the application of a bleaching agent to said paper. 85

6. The method of making safety paper 90 which consists in printing on the paper invisible warning indicia, which when discernible, would inherently nullify the paper, with a colorless chemical salt.

7. The method of making safety paper 95 which consists in printing matter thereon, which, when discernible, would inherently nullify the paper, with a colorless aniline salt.

8. The method of making safety paper 100 which consists in printing matter thereon with an aniline-chloride compound.

9. The method of making safety paper 105 which consists in printing warning indicia thereon with a colorless aniline-chloride compound, and stabilizing the warning indicia by the addition of a small quantity of sulphurous acid to said compound.

10. The method of making safety paper 110 which consists in printing normally invisible warning indicia thereon with an aniline chloride compound which is slightly acidic.

In witness whereof I have hereunto signed my name.

JOHN WALLACE NEFF.
